Co-pending U.S. Appl. No. 29/379,898, filed Nov. 26, 2010, entitled "Electrical Connector".

* cited by examiner

Primary Examiner — Thomas Johannes

(74) *Attorney, Agent, or Firm* — Leydig, Voit & Mayer, Ltd.

(57) **CLAIM**

The ornamental design for an electrical connector, as shown and described.

DESCRIPTION

FIG. 1 is a front, left, top-side perspective view of the electrical connector showing our new design;

FIG. 2 is a left side view thereof, the right side view being a mirror image of the left side view;

FIG. 3 is a top view thereof, the bottom view being a mirror image of the top view;

FIG. 4 is a rear view thereof;

FIG. 5 is a front view thereof;

FIG. 6 is front, left, top-side exploded perspective view thereof;

FIG. 7 is a left side exploded view thereof, the right side exploded view being a mirror image of the left side exploded view; and,

FIG. 8 is a top exploded view thereof, the bottom exploded view being a mirror image of the top exploded view.

The broken lines in the Figures depict interior portions of the connector that form no part of the claimed design.
